MULTIPLE COMPARTMENT REFRIGERATOR,
INCLUDING CONTROLS FOR THE REFRIG-
ERATING SYSTEM THEREOFCharles Passman, New York, N. Y., assignor to
S. F. Bowser & Company, Ltd., Toronto, On-
tario, Canada, a corporation of Canada

Application September 27, 1945, Serial No. 618,899

8 Claims. (Cl. 62—2)

1

This invention relates to a refrigerator, particularly to a method of circulating air through a multiple compartment refrigerator.

Heretofore, it has been the practice in a multiple compartment refrigerator to use a separate expansion coil and expansion valve in each compartment. However, using only one refrigerant, it is difficult to hold various compartments at different temperatures.

Applicant prefers to use a single, low temperature evaporator in one compartment and to hold the temperatures in the other compartments by circulating refrigerated air to each of them.

The refrigeration system shown is of the compression cascade type in which two separate refrigeration systems are used and in which the evaporator of one system cools the condenser of the other.

It is therefore an object of this invention to provide a multiple compartment refrigerator having gravitational or forced circulation of air.

It is another object of this invention to provide a multiple compartment refrigerator having interconnecting air ducts.

It is still another object of this invention to provide a multiple compartment refrigerator with interconnecting air ducts having thermostatically controlled dampers or shutters.

It is yet another object of this invention to provide a multiple compartment refrigerator with interconnecting air ducts having thermostats controlling dampers and a blower creating a flow of air between the compartments.

It is still another object of this invention to provide a multiple compartment refrigerator with an electrical circuit for coordination of the dampers and blower in interconnecting ducts to regulate the flow of air to each compartment.

Another object of the invention is to provide means for defrosting the evaporator coils.

These and other objects will become apparent from a study of this specification and the drawings which are attached thereto and made a part thereof and in which:

Figure 1 is a front view of the refrigerator, partially in section, showing the arrangement of the compartments, the air ducts, the thermostatically controlled dampers, and some of the mechanical elements.

Figure 2 is a right hand end view of the refrigerator, with the greater part of the housing removed, showing the arrangement of the refrigerating mechanism.

Figure 3 is a schematic diagram of the refrigerating mechanism.

2

Figure 4 is a modified form of the circulation and control means.

Figures 5 and 6 show the modified control mechanism for use with the circulation means of Figure 4.

Figure 7 is a wiring diagram of the arrangement shown in Figures 4, 5 and 6.

Referring to Figures 1, 2 and 3 of the drawings, the numeral 1 designates a base with a sheet metal housing 3 attached to and rising above the base. Louvres 4 are provided in the housing.

An electric motor 5 is mounted on the base and drives compressors 7 and 9. The driving mechanism is comprised of sheave 11 mounted on motor shaft 19 and connected to compressor sheave 13 by the belt 15.

Compressor 9 connects by way of conduit 21 with the air-cooled condenser 23, which is located directly in front of the fan 17, mounted on motor shaft 19. The condenser discharges into conduit 25 which splits into two branches 27 and 55. Conduit 27 discharges into the receiver 29. Conduit 31 is connected to the receiver on the discharge side and splits into conduits 33 and 45. One conduit 33 is joined to the expansion valve 35, which is connected by conduit 37 to coil 39 in the intercooler 41. Conduit 43 joins the outlet end of the coil to the suction side of compressor 9.

Conduit 45 is the second branch of conduit 31 and is connected to the suction side of the electrically driven pump 47 which discharges into conduit 49 which is wrapped around the evaporating coils 51 and which discharges through the check valve 53 into conduit 55. Thus warm liquid from the receiver 55 may be circulated to defrost the main evaporator 51.

The compressor 7 discharges through conduit 57 into the shell 59 of the intercooler 41. A conduit 61 leads from the intercooler shell to a receiver 63 which discharges through conduit 65 and float valve 70 into the float chamber 67. The float is designated by the numeral 69 and the liquid level by the numeral 71. The controller discharges through pipe 73 into the lower header 75 of the evaporating coil 51. The evaporating coil comprises a number of U-shaped tubes fixed at each end in header 75 which is in the form of a closed rectangular loop as viewed in Figures 1 and 3 of the drawings. An upper header 77 similar to 75 is connected with the lower header 75 by means of short tubes 79. A conduit 81 receives the evaporated refrigerant 55 discharged from the evaporating coil and is con-

nected to the suction side of compressor 7. The evaporator outlet into conduit 81 is placed at a higher level than the inlet 73. A tube 84 extends from conduit 81 on the suction side of compressor 7 to the vacuum switch 86 for controlling the motor 5.

The evaporator 51 is located in a quick-freeze chamber 83 having an insulated closure 85. All of the refrigerating chambers have double walls with insulation 91 therebetween. Of course, any suitable method of insulation may be used.

An air duct 93 extends downwardly inside the insulation between walls 95 and 97 and connects with a second compartment 99 which is a freeze hold compartment. A shutter 101 is connected by a crank 103, link 104, and lever 106 which is pivoted at 110 to a thermostat 105 so that expansion and contraction of the thermostat opens and closes the shutter. A spring 107 assists in returning the shutter to its closed position.

A duct 108 extends through insulated walls 109 and 111 near the bottom of compartment 99 and connects it with the bottom part of the regular refrigeration compartment 113.

Another duct 115 leads from the top of compartment 113 into duct 127. A damper 117 is disposed between ducts 115 and 127 and is opened and closed by crank 118, link 119, a lever 122 which is pivoted at 124, and thermostat 121, and is urged to closed position by a spring 123.

A third duct 125 connects compartments 83 and 99 and duct 127 connects ducts 115 and 125.

Thermostats 105 and 121 are opened to compartments 99 and 113 respectively.

The double walled construction around the refrigerated compartments with insulation 91 between is completed by walls 129, 130, 131, 133 and 135.

Access is provided to compartments 99 and 113 by doors 137 and 139 having hinges 141.

Operation of preferred form

With the motor 5 not operating, the vacuum in the evaporator 51, and lines 81 and 84 decreases, as the refrigerant vaporizes in the evaporator, to a point where the switch 86 is actuated, thereby starting motor 5. Motor 5 is the prime mover for compressors 7 and 9. The compressor 7 draws the vaporized refrigerant from the evaporator by way of pipe 81, compresses and discharges into the intercooler 41 by way of conduit 57. Here the vapor is cooled and liquified and passes into the receiver 63 by way of conduit 61. The liquid refrigerant passes through the conduit 65 through the float valve 70 into the float chamber 67, filling the chamber to the line 71 at which time the float 69 rises to close the valve 70.

In order for the float to close the valve, it is necessary that the section of the evaporator 51 be filled below the level of the liquid 71. It will be noted that the evaporator inlet conduit 73 is located at a lower point than the evaporator outlet conduit 81.

When the vacuum in the tube 84 increases to a predetermined point, the contacts in switch 85 are broken, shutting off the motor 5.

Compressor 9 compresses the vaporized refrigerant, circulates it through conduit 21 and condenser 23, which is cooled by the blast from fan 17 mounted on motor shaft 19. Conduits 25 and 27 conduct the liquified refrigerant to receiver 29, conduits 31 and 33 to expansion valve 35 through conduit 37 to the evaporator from which it passed by way of coil 39 of the inter-

cooler 41 and thence back to the compressor by way of conduit 43. The refrigerant passing through the coil 39 condenses the vapor which is forced into the inter-cooler shell 59 by the compressor 7 and cools the condensate.

The evaporator 51 is located in compartment 83 and this is designated as the fast-freeze compartment and is preferably held at a temperature of about -50° F. Shutter 101 is responsive to the expansion and contraction of the thermostat 105, which is open to compartment 99. Expansion of the thermostat caused by a rise in temperature in the freeze hold compartment above the required temperature of about zero degrees F. opens the shutter and permits passage of refrigerated air by gravity into compartment 99. Duct 125 located near the top of compartment 99 is open and in direct communication with the top of the fast freeze compartment so that the warm air displaced by that coming down duct 93 will flow into chamber 83. Contraction of the thermostat caused by lowering of the temperature in the freeze hold compartment closes the shutter and stops the circulation of refrigerated air.

As the temperature in compartment 113 rises above the normal temperature which is preferably about 40° F., the thermostat 121 expands and opens shutter 117, drawing air from compartment 99 through duct 108 while warm air passes through ducts 115, 127 and 125 to the top of chamber 99, thereby raising the temperature of compartment 99. Thermostat 105 expands and opens shutter 101, allowing free circulation of cold air from compartment 83 to compartments 99 and 113, and from the tops of both compartments to chamber 83 lowering the temperature of compartments 99 and 113 till the thermostats contract and, with the aid of springs 107 and 123, close shutters 101 and 117. The duct 127 prevents excessive circulation of 40° air through the freeze hold compartment. The temperature in compartment 83 is raised at the same time and will set in motion motor 5 and compressors 7 and 9, if necessary.

When it becomes necessary to defrost the evaporator coil, the electrically driven pump 47, controlled by a manually operated switch, pumps hot liquid from the receiver 29 by way of conduits 31 and 45 through conduit 49, which is wrapped around coil 51, and through check valve 53 and conduits 55 and 27 into the receiver. Circulation is continued until such time as defrosting is completed, when the switch is manually opened.

Operation modified form

A modified form of circulation system is shown in Figures 4, 5 and 6.

A blower or fan 143 driven by motor 145 is mounted in duct 147 which connects the freeze hold compartment 183 with the quick freeze compartment 148. Duct 147 and compartment 148 are similar to duct 83 and compartment 83 of Figure 1. The motor is mounted in compartment 149 with shaft 151 extending through wall 153 of the compartment and joining the motor and the blower.

The shutter 155 is operated by crank 156, link 157, and lever 158 which is pivoted at 154 and is connected at its other end to the armature of solenoid 161.

A duct 163 connects the tops of chambers 148 and 183. A shutter 168 is mounted in the duct and is operated by thermostat 167. The thermo-

stat acts on the operating crank 166 for switch 171 and motion is transmitted from the crank 166 to the crank 164 on the shutter by means of link 165. Thus, when the crank 166 is rotated clockwise by expansion of the thermostat, it will close switch 171 and open shutter 168. Spring 173 with one end fixed to post 175 retrieves the crank 166 upon retraction of the thermostat.

Ducts 177 and 178 and shutter 179 are similar in construction to ducts 115 and 127 and shutter 117 (Figure 1) and connect compartments 181 and 148. Crank 186, link 185, and switch lever 190 open the shutter 179 upon expansion of the thermostat 187. Downward movement of the lever 190 closes the switch 189. Spring 191 is fastened to the wall of duct 177 and lever 190 to close the shutter 179 and open the switch upon retraction of the thermostat.

All other elements used in the modification are identical to those shown in Figures 1, 2 and 3.

Figure 7 is a wiring diagram showing the circuit controlling the shutters and the blower. From the line 193, wire 195 leads to motor 145 which drives the blower 143 (Figure 4). From the wire 197, wire 200 leads to the thermostatically operated switch 189 and thence by wire 199 to motor 145. A second wire 201 leads to switch 171 which is in turn connected to wire 199 and the motor by wire 202. Switch 171 is operable by thermostat 167, while switch 189 is operated by thermostat 187. Solenoid 161 is connected in parallel with motor 145 by wires 203 and 205 and is energized upon the closing of switch 171 or 189.

In the modified form, shown in Figures 4, 5 and 6, compartments 181 and 183 correspond to compartments 113 and 99 of Figure 1 respectively.

As the temperature in compartment 183 rises, the thermostat 167 expands to close switch 171 which starts the blower motor 145 and energizes solenoid 161. It also opens shutter 168. The solenoid opens shutters 155 so as to admit cool air from compartment 148. Warm air from compartment 183 then passes through shutter 168 into compartment 148 by way of duct 163 to establish circulation through the compartment 183.

A rise in temperature in compartment 181 expands thermostat 187 which opens shutter 179 and closes switch 189. This energizes motor 145 and also the solenoid 161 which opens shutter 155. Cold air is blown from compartment 148 through the bottom of compartment 183 into 181 and out through ducts 177 and 163 into the compartment 148 to establish circulation and to refrigerate compartment 183.

A rise in temperature in compartment 181 expands thermostat 187 which opens shutter 179 and closes switch 189. This energizes motor 145 and also the solenoid 161 which opens shutter 155. Cold air is blown from compartment 148 through the bottom of compartment 183 into 181 and out through ducts 177 and 163 into the compartment 148 to establish circulation and to refrigerate compartment 183.

Lowering of the temperature in compartment 181 will cause thermostat 187 to close the respective shutter 179 and will open switch 189 to shut off the blower motor and deenergize the solenoid so that shutters 155 will also close.

It is obvious that various changes may be made in the form, structure and arrangement of parts without departing from the spirit of the invention. Accordingly, applicant does not desire to be limited to the specific embodiment disclosed

herein primarily for purposes of illustration; but instead, he desires protection falling fairly within the scope of the appended claims.

What I claim to be new and desire to protect by Letters Patent is:

1. In a mechanical refrigerator, a refrigerating unit having an evaporator, a refrigerated compartment for said evaporator, a second refrigerated compartment, ducts connecting said compartments for circulating air, a shutter movable between open and closed position and thermostatically responsive to the temperature in said second compartment for regulating said circulation, and a blower in one of said ducts operating simultaneously with the opening of said shutter to force circulation of said air.
2. In a mechanical refrigerator, a refrigerating unit having an evaporator, a fast freeze compartment housing said evaporator, a freeze hold and a normal refrigerating compartment, ducts interconnecting said compartments, means comprising shutters movable between open and closed positions in said ducts connecting said fast freeze and freeze hold compartments and connecting said freeze hold and said normal refrigerating compartments, a blower set in motion by opening of either of said shutters, and means for opening said shutters between said fast freeze and freeze hold compartments upon opening of the shutter between the freeze hold and the normal refrigerating compartments.
3. In a mechanical refrigerator multiple refrigerating compartments, a refrigerating unit having an evaporator in one of said compartments, means responsive to the high and low temperature limits in each of said compartments regulating the flow of air through said compartments and operating said refrigerating unit.
4. In a refrigerating unit of the cascade type, a refrigerant circuit having an evaporator, a secondary refrigerant circuit having a receiver and an expansion valve and a pump connected to said second circuit between said receiver and expansion valve circulating liquid from said receiver through a conduit encircling said evaporator to defrost said evaporator.
5. In a refrigerating unit of the cascade type, a refrigerant circuit having an evaporator, a secondary refrigerant circuit having a receiver and means including a pump and a conduit encircling said evaporator for circulating hot liquid from said receiver around said evaporator to defrost said evaporator.
6. In a mechanical refrigerator, a refrigerating unit having an evaporator, a fast freeze compartment refrigerated by said evaporator, additional freeze hold and normal refrigeration compartments, means for refrigerating said last named compartments from said fast freeze compartment comprising upper and lower ducts connecting the top of the fast freeze and freeze hold compartments and the bottoms thereof, respectively, additional upper and lower ducts connecting the tops of the freeze hold and normal refrigeration compartments and the bottoms thereof, respectively, a damper in the lower duct of said first named compartment, a second damper in the upper duct of said last named compartment, thermostatic means in said freeze hold compartment for controlling the first mentioned damper and additional thermostatic means in said normal refrigeration compartment for controlling said second mentioned damper.
7. In a mechanical refrigerator, a refrigerating unit having an evaporator, a fast freeze com-

partment refrigerated by said evaporator, additional freeze hold and normal refrigeration compartments, means for refrigerating said last named compartments from said fast freeze compartment comprising upper and lower ducts connecting the top of the fast freeze and freeze hold compartments and the bottoms thereof, respectively, additional upper and lower ducts connecting the tops of the freeze hold and normal refrigeration compartments and the bottoms thereof, respectively, a damper in the lower duct of said first named compartment, a second damper in the upper duct of said last named compartment, thermostatic means in said freeze hold compartment for controlling the first mentioned damper, additional thermostatic means in said normal refrigeration compartment for controlling said second mentioned damper, a fan and means operable by either of said thermostatic means for energizing said fan.

8. In a mechanical refrigerator, a refrigerating unit having an evaporator, a fast freeze compartment refrigerated by said evaporator, additional freeze hold and normal refrigeration compartments, means for refrigerating said last named compartments from said fast freeze compartment for controlling the first mentioned damper, additional thermostatic means in said normal refrigeration compartment for controlling said second mentioned damper, a fan and means operable by either of said thermostatic means for energizing said fan.

15

ment comprising upper and lower ducts connecting the top of the fast freeze and freeze hold compartments and the bottoms thereof, respectively, additional upper and lower ducts connecting the tops of the freeze hold and normal refrigeration compartments and the bottoms thereof, respectively, a damper in the lower duct of said first named compartment, a second damper in the upper duct of said last named compartment and means exposed to the air of each of said additional compartments connected to actuate one of said dampers for regulating the temperature of its respective compartment.

CHARLES PASSMAN.
